UNITED STATES PATENT OFFICE.

HARLOW T. STOKES, OF NEWARK, NEW JERSEY.

AEROPLANE.

1,169,883.

Specification of Letters Patent.

Patented Feb. 1, 1916.

Application filed March 9, 1910. Serial No. 548,156.

To all whom it may concern:

Be it known that I, HARLOW T. STOKES, a citizen of the United States, residing in Newark, county of Essex, and State of New Jersey, have invented certain new and useful Aeroplanes, of which the following is a specification.

This invention is an aeroplane embodying a novel construction and organization of planes whereby increased weight sustaining or lifting power is secured, coupled with a reduction of resistance to the air during flight, suitable provision being made for controlling the planes at the will of the aviator in order that the craft may be steered in any direction, and at a desired elevation, so as to sail with or against the wind or air pressure.

An important feature of the invention resides in the main or weight-sustaining planes, comprising preferably three planes so disposed with relation to each other as to produce a space between them. Two of said planes extend outwardly from the main frame or car of the craft, said planes meeting each other at their inner ends so as to produce a dihedral angle, or the inner end of one plane may be spaced relatively to the corresponding end of the other plane, the angle being the same in either arrangement. The third plane is positioned above the two inwardly converging (or outwardly diverging) planes just mentioned, so that the third plane extends across the adjacent or meeting ends of the two first named planes; and said third plane may be joined at its end portions to the outwardly diverging planes at points intermediate the ends of said latter planes, but it is preferred that the end portions of the third plane be spaced relatively to said outwardly diverging planes, it being obvious that the ends of said third plane should be connected, as by struts, to the diverging planes. It is preferred to curve each of said three planes, that is to say, each plane is curved from end to end, or longitudinally, and, furthermore, each plane is curved transversely, or from front to rear. The use of the third plane in conjunction with the two outwardly diverging planes increases area of surface for wind or air pressure by reason of the fact that the under surfaces of all the planes are exposed, and said surfaces are curved both longitudinally and transversely

so as to secure the maximum effect of wind or air pressure upon said surfaces.

Another part of the invention consists of auxiliary planes, preferably triangular in shape, positioned at the rear of two of the main planes and controllable separately at will for the purpose of turning said auxiliary planes at an angle to the main planes.

Another part of the invention consists of wing tips positioned at the outer end portions of two main planes. Said wing tips are controlled by the operator, and according to my invention, they move in unison with each other, to the end that said planes may both be moved downward simultaneously, or upward simultaneously, whereby the wing tips are controlled at the will of the aviator. The object of said wing tips is to alter at will the end portion of each main plane with respect to the general shape thereof, viz., forming as they do a continuation of each main plane and drawn downward slightly below the level of the end of said main planes, the total lateral curvature of the under side of each main plane A B is increased. When raised slightly above the end of each main plane, the total lateral curvature of each main plane is decreased, it being understood that these wing tips are designed to be moved to a position determined by circumstances to be the most efficient in effect in securing the lateral balance of the machine due to certain weather conditions, winds, and the direction of the wind with reference to the direction of flight, and after being so set the wing tips remain in such positions until the conditions of the wind, weather or flight require a different setting with reference to the angle of the under curvature of each main plane. From the nature of the connections, said wing tips cannot be used as lateral stabilizers alone, as they act equally on each side of the machine at one and the same time. Any suitable locking device, such as a sector and pawl (not shown), may be used to lock the controlling lever for the wing tips in any desired position, and thereby, also, through the cable connections lock the wing tips in the desired position for the moment.

Another part of the invention consists of elevating planes positioned in advance, and to the rear, of the main planes, each of said

elevating planes being hung for movement on a horizontal axis which is at a right angle to the longitudinal axis of the craft. Said elevating planes are controllable by the operator, and the operating devices therefor are adapted for shifting the planes simultaneously and in corresponding directions, whereby the craft may be caused to ascend or descend.

10 The invention consists, also, of auxiliary planes positioned in front of the main planes, said auxiliary planes being at opposite sides of the front elevating plane, and said front auxiliary planes being connected 15 operatively with the rear auxiliary planes for simultaneous movement therewith when the auxiliary planes are shifted by the aviator.

It is obvious that the auxiliary planes positioned in front of the main plane and on each side of the center of the aeroplane may be changed in position without altering the purpose or use of this part of the invention.

20 Various other parts of the invention not heretofore mentioned will appear in the course of the subjoined description.

25 In the accompanying drawings I have illustrated one practical embodiment of the invention, but the construction shown there- 30 in is to be understood as illustrative, only, and not as defining the limits of the invention.

35 Figure 1 is a front elevation of my new aeroplane. Fig. 2 is a side elevation thereof. Fig. 3 is a plan view, and Fig. 4 is a detail cross section on an enlarged scale and in the plane of the dotted line 4—4 of Fig. 3.

40 The weight-supporting elements of my aeroplane consist of three main planes, A, B, C, which are associated with a suitable frame, D, adapted to support a car, E, when the craft is in flight.

45 In one embodiment of the invention an engine or motor of any suitable type, indicated by the reference character, F, is positioned within the forward part of said car, and to the shaft, f, of this motor are geared counter shafts, f¹, which extend outwardly to the shafts, f², of propellers, F², the latter being positioned at opposite sides of the longitudinal axis of the craft, and forwardly of the weight-supporting planes.

50 Said planes, A, B, C, constitute an important part of the invention. Planes, A, B, extend outwardly from frame, D, at the respective sides thereof, it being preferred to extend the inner ends of planes, A, B, to the axial line of the craft, although said inner ends of planes A, B, may be separated so as to leave an intervening space between said ends, whereby the inner ends or roots of planes A B may be attached to the side portions of a central car or fuselage of the aeroplane. Planes, A, B, are shown in Figs.

1 and 3 as extending outwardly and upwardly from the medial line of the craft, said planes converging downwardly and inwardly toward each other, or otherwise expressed, said planes may diverge upwardly and outwardly as best shown in Fig. 1. The other main plane, C, is positioned over the inner end portions of planes, A, B, and is spaced relatively thereto, so as to produce a space between the upper plane C and the diverging planes A, B.

55 Each main plane, A, B, C, is, preferably, curved longitudinally, or from end to end thereof, and, furthermore, each plane is curved transversely, or from front to rear, the longitudinal curvature of said planes being clearly shown in Fig. 1, and the transverse curvature being indicated in Figs. 2 and 4.

60 It will be understood that the shape of the planes just mentioned is illustrated diagrammatically as a single surface in the drawings for the sake of clearness only. As a matter of construction, however, these planes are composed of skeletonized frames covered on the top and bottom with suitable 90 material, each main plane being shaped so as to produce a plane of the bird-wing type, the same being essentially a natural and proper way of obtaining the most efficient results in lifting power and natural stability. The planes A, B are shown as having a variable curvature from end to end and a variable curvature from front to rear, said planes being substantially free from obstructions to the passage of the air at this 100 point, and said bird-wing type of plane securing a mechanical wing of the greatest efficiency for lifting purposes, stability in flight, and minimum resistance to the forward progress of the machine through the 105 air.

65 The third plane C is similar in construction, being of arched form and possessing a moderate curvature, a curve of about 18 inches in 16 feet having been found to be 110 most efficient. The end portions of the plane C are open or spaced with respect to planes A, B to facilitate the free passage of air both laterally and horizontally. It is apparent that the end portions of plane C 115 may be attached to some portion of planes A, B intermediate the ends of the latter, as for example by struts, braces, or other suitable means, such as D in Figs. 1 and 2.

70 It will be understood that all the planes including the ailerons and wing tips are provided with double covered surfaces, each being composed of a skeleton frame covered on both sides with suitably treated or varnished fabric, metal sheets, or other suitable 125 covering.

75 The plane C is positioned in such relation to planes A, B that the end portions of said

plane C are spaced relative to planes A and B to allow the free egress of air over said planes A and B and beneath the end portions of plane C.

- 5 As best shown in Fig. 3, each plane, A, B, is tapering in shape, the widest portion of each plane being at the inner end thereof. The front edge, a , of each plane, A, B, C, is at a right angle to the longitudinal axis 10 through the craft, but each plane, A, B, is provided with an inclined rear edge, a' , the latter extending at an angle to the longitudinal axis of the craft so as to produce a plane which in plan view decreases in width 15 from the inner end toward the outer end, the outer end of said plane being the narrower. Plane, C, is provided with a front edge, c , which is at a right angle to the longitudinal axis of the craft, as shown in Fig. 3, but the 20 rear edge, c' , of said plane, C, is slightly convex, thus resulting in a plane possessing the curvature characteristic of a bird wing.
- G, G' are auxiliary planes positioned at the rear of main planes, A, B, said auxiliary 25 planes being hinged directly to the main planes, as at g , whereby the auxiliary planes are carried by the respective main planes, and said auxiliary planes are adapted for movement up and down at the rear of the main 30 planes. The auxiliary planes are precluded from moving upwardly above the main planes, A, B, by certain stop devices, herein shown as cords or cables, g' , attached to the auxiliary planes and to certain arms, g^2 . 35 Furthermore, the auxiliary planes are normally lifted by the action of springs, g^3 , all as shown diagrammatically in Fig. 4. The auxiliary planes coöperate with the main planes, A, B, to substantially increase the 40 area of the weight-supporting surface, but said auxiliary planes serve the important function of retarding planes in order to assist in arresting the motion of the craft when sweeping downward toward the earth 45 prior to coming to rest so that the operator may alight. For this purpose the auxiliary planes are controllable at will, and, as shown in Fig. 3, certain operating cables, g^4 , are attached to the free rear edges of said planes. 50 The cables, g^4 , extend over guide pulleys, g^5, g^6, g^7 , the ends of said operating cables being attached to knee levers, G^2, G^3 , which are within convenient reach of the aviator adapted to occupy the cock pit, e , of the car, 55 E, see Fig. 3. The knee levers are operated independently by the aviator, but it is apparent that the knee levers may be operated simultaneously so that at the end of a flight and while alighting and running along the 60 ground both ailerons may be brought down at a right angle to the main plane, thus producing a resistance to the forward movement of the machine, and securing the effect of a wind brake.

Extending upwardly from the bow of the 65 car, E, is a suitable supporting frame, h , and rising from the rear or stern part of the car is another supporting frame, h' , see Fig. 2. On these frames h, h' are supported elevating planes, H, H' , which are positioned in 70 front and rear, respectively, of the main or weight-supporting planes, A, B, C, and the auxiliary planes, G, G' . Each plane, H, H', is curved longitudinally, or from end to end, as shown in connection with the plane, H, in 75 Fig. 1, and, furthermore, each plane is curved transversely, or from front to rear, as shown in Fig. 2. Said planes are mounted for movement on horizontal axes in 80 frames, h, h' , and with said planes are associated the operating cables, h^2 , which extend around guides, h^3, h^4, h^5, h^6 , to a hand lever, J^2 , see Figs. 2 and 3. The lever is positioned within cock pit, e , to be in convenient reach 85 of the aviator, and by movement of the lever in one direction, the elevating planes may be tilted downwardly and forwardly, whereas the reverse movement of lever enables the elevating planes to be tilted upwardly and rearwardly. Obviously, when 90 the elevating planes, H, H', occupy horizontal positions, the craft will have a tendency to fly in a substantially horizontal direction; by tilting the planes upwardly and rearwardly they are inclined to the horizontal 95 plane of the craft, and the pressure of the wind or air against their under sides has a tendency to cause the craft to travel in an upward direction, but, an adjustment of the planes to a downwardly and forwardly inclined position causes the air or wind to exert pressure on the top surface of the planes, and thereby directs the craft in a downward path. As shown more clearly in 100 Fig. 1, each steering plane, H, H', is hung 105 for movement on a horizontal axis, which axis is at right angles to the longitudinal axis of the craft. Each steering plane is provided with a straight front edge, inclined rearwardly diverging end edges, and curved 110 rear edges, this particular form of the plane having certain advantages from a practical standpoint.

In addition to auxiliary planes, G, G' , the craft is provided with other auxiliary 115 planes, I, I' , the latter being positioned in front of main planes, A, B, and below the steering plane H. Said auxiliary planes, I, I' , are hinged to an outwardly extending supporting member, I^2 , which is attached 120 to the bow end of car, E, and extends in inclined directions outwardly and upwardly therefrom, as shown in Fig. 1. Said planes, I, I' , are hinged to supporting member, I^2 , so as 125 to move on horizontal axes, the axis of movement of each plane, I, I' , being at a right angle to the longitudinal axis of the car.

Auxiliary planes, I, I', are adapted, preferably, for movement simultaneously with auxiliary planes, G, G'. This is secured by employing cables, *i*, attached to planes, I, I', 5 near their rear edges and extending over suitable guides, *i'*, *i''*, to the cables, *g*', said cables, *i*, being attached to said cables *g*', whereby planes, I, I', and G, G', are adapted for operation by knee levers, G², G³. As 10 shown in Fig. 3, the auxiliary plane, G, at one side of the craft and auxiliary plane, I, at the same side of the craft are connected to knee lever, G², whereby planes, G, I, will be operated simultaneously by said lever. 15 In like manner, the auxiliary planes, G', I', on the same side of the craft are connected with the other knee lever, G³, so that the operation of lever, G³, will simultaneously move said auxiliary planes, G', I'. 20 J, J' designate wing tip planes positioned at the outer ends of the main planes, A, B, respectively. Each wing tip plane is positioned for its longitudinal axis to be substantially parallel to the longitudinal 25 axis of car, E, and said planes are hinged or pivotally connected at their inner edges to the outer ends of the respective planes, A, B, the axes of movement of balancing planes, J, J', being parallel to the longitudinal axis 30 of the car. To the planes, J, J', are attached operating cables, *j*, which extend to the middle part of car, E, and are operatively connected to a shaft H², having hand wheel, H³, or other suitable controlling member, 35 positioned within cockpit, *e*, so as to be within convenient reach of the aviator, said shaft, H², being shown more clearly in Fig. 2. Both wing tip planes, J, J', are connected with a single hand shaft, H², so that 40 the planes may move up and down through an arc of 120°, said planes moving in unison with each other. The operating devices for wing tip planes, J, J', are so arranged and proportioned that each plane moves an equal 45 extent at the same time and in the same direction, it being understood that a movement of the shaft, H², in one direction will pull down planes, J, J', simultaneously, whereas a movement of the shaft in an opposite direction will allow the planes to 50 move upwardly simultaneously. When planes, J, J', are moved downwardly, more or less as required, they conform to the longitudinal curvature of main planes, A, B, 55 substantially as shown in Fig. 1, and should the planes be moved downwardly to a still further extent, they will assume angular positions to the outer end portions of planes, A, B. The main purpose of the planes, J, J', 60 is to increase the curvature of the end portions of the main planes when sailing downwardly at a slight angle. It may be remarked that planes, J, J', are useful, mainly, when gliding down from a height at a steep 65 angle, and they have something of the ef-

fect of a parachute in the descent of the craft.

Extending upwardly from car, E, is a rudder post, *k*, which carries a vertical rudder, K. To the lower part of this rudder post are attached operating cables, *k'*, extending forwardly to a foot lever, K', shown in dotted lines in Fig. 3, the same being positioned within cockpit, *e*, of the car, whereby the operator is enabled to change the position of rudder, K, by the pressure of the feet against said lever, K'.

It should be remarked that each of the planes employed in my aerial craft is curved from end to end, or longitudinally, and from front to rear, or transversely, the curvature of said plane being on a radius to be determined by actual conditions of use.

In cross section, frame, D, and car, E, are triangular, with the vertex of the triangle at the bottom of car, E. Said car, E, may, however, be of any suitable construction, but said car is shown in the drawings as substantially canoe shaped in order that the craft may float on the water should it descend when over a river or other body of water. The canoe shaped car is constructed so that it will afford the least resistance to the movement of the craft through the air, and in the embodiment shown in the drawings, said car, E, is provided at its forward portion with inclined sides, *e'*, diverging from the bow rearwardly. The diverging sides, *e'*, *e'*, extend from the bow rearwardly to a point below the weight-carrying planes, A, B, C. Below said planes the sides, *e*', of the car are parallel to each other to a point opposite cockpit, *e*, but in rear of the cockpit the sides, *e*'' of the car converge toward the stern, the angle of the sides, *e*'' being less than the angle of the bow portion, *e'*, of the car. The flotation of the car is increased by the employment of cylinders, L, positioned at the respective sides of the car, and suitably attached to the respective sides thereof. Said cylinders are adapted to serve as reservoirs for the hydrocarbon or other fluid combustible which is to be supplied to the cylinders of engine, F, but said cylinders, L, perform the function, mainly, of floats to increase the buoyancy of the craft when used as a marine vessel.

As is usual in crafts of this character, the car is provided with a suitable running gear, M, below the forward part of the car, and at the bow and stern of said car are provided skids, N, said skids being composed of yieldable material and so attached to the car that they will serve as shock absorbers when the craft comes into contact with the earth at the time of alighting.

It is thought that the operation and advantages of this invention will be readily understood from the foregoing description taken in connection with the drawings.

Having thus fully described the invention, what I claim as new, and desire to secure by Letters Patent is:

1. In an aeroplane, a plurality of main weight-supporting planes, two of which diverge outwardly, and a third plane being positioned above said diverging planes, a plurality of propellers positioned on opposite sides of the longitudinal axis of the aeroplane, a plurality of auxiliary planes positioned at the rear of said outwardly diverging weight-supporting planes, each auxiliary plane being hinged for movement on a horizontal axis, and means for turning said auxiliary planes to an inclined position with respect to said weight-carrying planes. 5
2. An aeroplane embodying a plurality of main weight supporting planes two of which diverge outwardly and a third plane positioned over said diverging planes, said third plane being in a predetermined fixed relation to said diverging planes, wing tip planes hinged to the diverging planes at the outer ends thereof, said wing tip planes being positioned distant from the ends of the third plane, and means for shifting the wing tip planes in the same direction and at the same time whereby in one position of said wing tip planes the latter constitute extensions or prolongations of the main diverging planes. 20
3. An aeroplane embodying a plurality of three relatively fixed main planes two of which diverge outwardly and a third plane positioned over said diverging planes and spaced relatively thereto, each plane being curved lengthwise and crosswise, wing tip planes hinged to the diverging planes at points distant from the ends of said third plane, and means for controlling said wing tip planes whereby the positions of said wing tip planes relatively to the other planes may be changed at will. 35
4. In an aeroplane, a plurality of weight-supporting planes each curved longitudinally, two of said planes occupying outwardly diverging relation to each other, and a third plane positioned above the diverging planes, longitudinally curved balancing planes positioned at the outer ends of the two first named planes, and means for imparting movement to the balancing planes simultaneously and in the same direction whereby the balancing planes are adapted 50 to be moved into position wherein the longitudinal curvature thereof corresponds to the arc of the first two planes. 55
5. In an aeroplane, two weight-supporting planes, curved lengthwise and diverging with respect to each other, and a third plane positioned over the inner portions of said diverging planes, longitudinally curved balancing planes positioned at the outer ends of the two first named planes, and means for imparting movement to the bal- 60
- ancing planes simultaneously and in the same direction whereby the balancing planes are adapted to be moved into position wherein the longitudinal curvature thereof corresponds to the arc of the first two planes. 70
6. In an aeroplane, two longitudinally curved weight-supporting planes positioned in diverging relation to each other, and a third plane over the inner portions of said diverging planes, said third plane being 75 curved longitudinally and being spaced, for the major part of its width, relative to said diverging planes, longitudinally curved balancing planes positioned at the outer ends of the two first named planes, and means for 80 imparting movement to the balancing planes simultaneously and in the same direction whereby the balancing planes are adapted to be moved into position wherein the longitudinal curvature thereof corresponds to 85 the arc of the first two planes.
7. An aeroplane embodying a plurality of three relatively fixed main planes two of which diverge outwardly and a third plane positioned over said diverging planes, the 90 end portions of said third plane being spaced relatively to said diverging planes, and wing tip planes hinged at the outer ends of said diverging planes, each wing tip plane being curved in the same general direction as the 95 diverging plane to which it is hinged, said hinged connections between the wing tip planes and the diverging planes being distant from the respective end portions of said third plane. 100
8. In an aeroplane, two relatively diverging weight-supporting planes, a third weight-supporting plane over said two planes, each plane being curved lengthwise and transversely, and balancing planes positioned at the outer ends of the two first named planes, each balancing plane being curved and movable to a position wherein its curvature corresponds to the longitudinal curvature of one of the two first named 110 weight-supporting planes so as to form an extension thereof. 105
9. In an aeroplane, a plurality of not less than three weight-carrying planes, two of which are positioned in diverging relation, 115 and the remaining plane being over the two said planes and co-operating therewith to stiffen the same, auxiliary planes positioned at the rear of the two diverging planes, means for operating said auxiliary planes 120 whereby they may be positioned at an angle to the surfaces of the diverging planes, balancing planes hinged at the outer ends of the two first named planes and forming extensions thereof, and means for operating 125 the balancing planes simultaneously and in the same direction.
10. In an aeroplane, a plurality of weight-supporting planes, each decreasing in width toward the outer end thereof, a plurality of 130

- auxiliary planes positioned at the rear of, and movable at an angle to, said weight-supporting planes, whereby the auxiliary planes may exert a retarding effect on the 5 flight of the craft, each balancing plane increasing in width toward its outer end, balancing planes positioned at the outer ends of the weight-supporting planes, and separate operating means for the auxiliary 10 planes and the balancing planes.
11. An aeroplane embodying a plurality of main planes two of which diverge outwardly and a third plane positioned over said diverging planes and spaced relatively 15 thereto, wing tip planes hinged at the outer ends of said diverging planes, each wing tip being curved transversely from front to rear and said wing tip being curved in the same general direction as the diverging plane to 20 which it is hinged.
12. In an aeroplane, a plurality of weight-supporting planes, two of which diverge relative to each other and a third positioned over said diverging planes, said diverging 25 planes decreasing in width toward the outer ends thereof, a plurality of auxiliary planes at the rear of said diverging weight-supporting planes, each auxiliary plane being substantially triangular and extending for 30 substantially the length of one diverging plane, means for shifting the positions of said auxiliary planes relative to the weight-supporting planes, balancing planes positioned at the outer ends of the weight-supporting 35 planes and beyond the ends of the triangular auxiliary planes, and means for operating the balancing planes.
13. An aeroplane embodying three relatively fixed weight-carrying planes two of 40 which diverge outwardly, and the third plane being positioned over said diverging planes and spaced relatively thereto, each plane being curved in the direction of its length, wing tip planes hinged to said diverging planes at points distant from the 45 respective ends of said third plane, and means for operating said wing tip planes for moving them downwardly so as to form extensions of the diverging planes.
- 50 14. An aeroplane embodying three relatively fixed weight-carrying planes two of which diverge outwardly, and the third plane being positioned over said diverging planes and spaced relatively thereto, movable wing tip planes hinged to said diverging planes at points distant from the 55 respective ends of said third plane, means for operating said wing tip planes for moving them downwardly so as to form extensions of the diverging planes, other 60 movable planes hinged to the rear of said diverging planes, and means for limiting or arresting the movement of certain of said movable planes with respect to said diverging planes.
- 65 15. In an aeroplane, three longitudinally

curved weight-supporting planes two of which occupy diverging relation to each other and the third is positioned over the said diverging planes, a plurality of auxiliary planes each positioned at the rear of 70 one of said diverging planes, means for separately adjusting the auxiliary planes, whereby said planes may assume different positions and at an angle to the diverging planes, balancing planes positioned at the 75 outer ends of the diverging planes and beyond the auxiliary planes, and means for operating the balancing planes simultaneously and in the same direction, whereby the balancing planes are adapted to be moved 80 downwardly so as to conform to the curvature of the diverging planes.

16. In an aeroplane, a plurality of weight-supporting planes, a plurality of auxiliary planes at the rear of said weight-supporting 85 planes, each auxiliary plane being curved lengthwise and transversely.

17. In an aeroplane, a plurality of weight-supporting planes two of which are in diverging relation to each other and a 90 third plane positioned over said diverging planes, auxiliary planes having hinged connection with said diverging planes, means for operating the auxiliary planes, balancing planes positioned at the outer ends of 95 the weight-supporting planes and beyond the auxiliary planes, and means for operating the balancing planes simultaneously and in the same direction.

18. In an aeroplane, the combination of 100 weight-supporting planes positioned in diverging relation to each other, each plane having an inclined rear edge so that said plane decreases in width toward the outer end thereof, substantially triangular auxiliary planes positioned at the rear of the diverging planes, each auxiliary plane being hinged to the inclined edge of one diverging plane, a retractor for lifting each auxiliary plane, a stop device for limiting the movement of each auxiliary plane, said retractor and stop device operating to retain each auxiliary plane in substantial alignment with the diverging plane to which it is attached, and means for operating said auxiliary 110 planes.

19. In an aeroplane, two relatively diverging weight-supporting planes, a third weight-supporting plane over said diverging planes, elevating planes positioned at the front and rear of all the weight-supporting planes, means for adjusting the elevating planes, balancing planes positioned at the outer ends of the two diverging planes, and means for operating the balancing planes 125 simultaneously and in the same direction.

20. In an aeroplane, a plurality of weight-supporting planes, two of which diverge outwardly and a third plane being positioned over the inner adjacent end portions 130

- of said diverging planes, elevating planes at the front and rear of said weight-supporting planes and each adapted for movement on a horizontal axis, and means for 5 operating the elevating planes simultaneously and in the same direction, balancing planes positioned at the outer ends of the two diverging planes, and means for operating the balancing planes simultaneously 10 and in the same direction.
21. In an aeroplane, two relatively diverging weight-supporting planes, longitudinally curved balancing planes at the outer distant ends of said diverging planes, and 15 means for operating the balancing planes simultaneously and in the same direction.
22. In an aeroplane, two relatively diverging and longitudinally curved weight-supporting planes, longitudinally curved 20 balancing planes hingedly supported at the distant ends of said weight-supporting planes, and operating means connected to said balancing planes whereby they are operated simultaneously and in the same direction.
- 25 23. An aeroplane embodying three weight-carrying planes two of which diverge outwardly and the third plane is positioned over said diverging planes and is 30 spaced relatively thereto, each plane being curved in the direction of its length, wing tip planes hinged to said diverging planes at the outer ends thereof, each wing tip plane being curved in the same general direction as the curvature of the diverging plane to which it is hinged, and means for 35 operating the wing tip planes so as to move the same downwardly so as to form extensions or prolongations of the diverging 40 planes.
24. In an aeroplane, the combination of two relatively diverging weight supporting planes each curved in the direction of the length thereof, auxiliary planes hinged to 45 the rear edges of the diverging planes and positioned at the respective sides of a longitudinal medial line through the machine, each auxiliary plane being curved lengthwise, a third weight supporting plane positioned 50 above the diverging planes, the end portions of said third plane terminating intermediate the end portions of the diverging planes and the auxiliary planes, means for operating said auxiliary planes whereby 55 they are movable into positions inclined to the surfaces of the diverging planes, and other auxiliary planes positioned in advance of the diverging planes and at the respective sides of the longitudinal medial line 60 through the machine.
25. In an aeroplane, a plurality of weight-supporting planes, auxiliary planes positioned at the rear of the weight-supporting planes, an elevating plane at the front of the 65 weight-supporting planes, other auxiliary planes positioned in advance of and disconnected from the weight-supporting planes, the auxiliary planes at the front and rear of the weight-supporting planes being at the respective sides of the longitudinal axis 70 through the machine, and balancing planes positioned at the outer ends of the weight-supporting planes.
26. In an aeroplane, the combination of weight-supporting planes, auxiliary planes 75 positioned at the rear of said weight-supporting planes, other auxiliary planes positioned in advance of, and disconnected from, said weight-supporting planes, the auxiliary planes at the rear and the front of said weight-supporting planes being arranged at the respective sides of a longitudinal medial line of the machine, and connecting means between said auxiliary planes, one of said means connecting a front auxiliary plane on 80 one side of the medial line with a rear auxiliary plane on the same side of said medial line, whereby the two pairs of auxiliary planes are operated simultaneously.
27. An aeroplane having main weight- 90 supporting planes extending at the opposite sides thereof, forming a dihedral angle with each other, the planes curving from end to end, curved balancing planes positioned at the outer ends of said main weight-supporting 95 planes, and means for operating the balancing planes simultaneously and in the same direction.
28. In an aeroplane, the combination of two main planes disposed in diverging relation to each other, each main plane being curved longitudinally, a third longitudinally curved main plane positioned over the diverging planes, the ends of said third plane terminating opposite to the diverging 100 planes and intermediate the ends thereof, curved balancing planes positioned beyond the ends of the third main plane, each balancing plane being hinged to the outer end portion of one of said diverging planes, 105 and means for simultaneously operating said balancing planes whereby they may at one movement be drawn downwardly for the curvature thereof to correspond to the curvature of the main diverging planes. 110
29. An aeroplane having two main weight-supporting planes extending at the opposite sides thereof, a third weight-supporting plane extending over and connected to the main planes and forming in connection therewith a dihedral angle, auxiliary planes hinged at the rear edges of the two main weight-supporting planes and disconnected from the third weight-supporting plane, and knee operated levers for changing the 115 positions of the auxiliary planes relative to the two main weight supporting planes. 120
30. An aeroplane having main weight-supporting planes extending at the opposite sides thereof and forming a dihedral angle 125
- 130

with each other, the planes curving from end to end and from front to rear, with the concave sides of the planes facing downwardly, said planes decreasing in width toward their outer ends, auxiliary planes hinged at the rear ends of said main weight-supporting planes, and knee operated levers for adjusting the positions of the auxiliary planes relative to the weight-supporting planes.

31. An aeroplane having two main weight-supporting planes extending at the opposite sides thereof, a third weight-supporting plane arched over the inner end portions of the main planes and secured intermediate the ends thereof, auxiliary planes hinged at the rear of the two main planes, means for adjusting the auxiliary planes, balancing planes hinged at the outer ends of the two main planes, and means for adjusting the balancing planes, said auxiliary planes and the balancing planes being disconnected from the third weight-supporting plane.

32. An aeroplane having two main weight-supporting planes curving upwardly and outwardly at the respective sides thereof, a third weight-supporting plane arched over the inner portions of the main planes, curved balancing planes hinged at the outer ends of the two main planes and positioned beyond the third plane, curved auxiliary planes hinged at the rear edges of the two main planes, and separate means for operating the balancing planes and the auxiliary planes.

33. An aeroplane having main weight-supporting planes extending at the respective sides thereof and forming a dihedral angle with each other, each plane decreasing in width from the inner to the outer ends thereof, auxiliary planes hinged at the rear edges of the main planes and adapted, when extended rearwardly therefrom, to form planes of approximately uniform width, and knee operated levers for adjusting the auxiliary planes.

34. An aeroplane having main weight-supporting planes extending at the respective sides thereof and forming a dihedral angle with each other, auxiliary planes positioned along the rear edges of the main planes and hinged thereto, and knee operated levers for adjusting the auxiliary planes independently or simultaneously at will.

35. An aeroplane having main weight-supporting planes extending at the respective sides thereof and forming a dihedral angle with each other, and auxiliary planes positioned at the rear edges of the main planes and hinged thereto, each of said planes being curved from end to end and from front to rear.

36. An aeroplane embodying three relatively fixed weight-carrying planes two of

which diverge outwardly, and the third plane being positioned over said diverging planes and spaced relatively thereto, each plane being curved in the direction of its length, movable wing tip planes hinged to said diverging planes at points distant from the ends of said third plane, each wing tip plane being curved in the same general direction as the diverging planes, means for operating the wing tip planes so as to draw them downwardly and to form extensions of said diverging planes, other movable planes hinged to the diverging planes at the rear thereof, and means for limiting the movement of certain of said movable planes to preclude the latter from lifting above a line horizontal with respect to the diverging planes.

37. An aeroplane having main weight-supporting planes extending upwardly and outwardly at the respective sides thereof, and a balancing plane hinged to the outer end of each main plane, each of said planes being curved from end to end and from front to rear.

38. An aeroplane having main weight-supporting planes extending at the respective sides thereof, a third weight-supporting plane arranged over the main planes and forming in connection therewith a dihedral angle, auxiliary planes hinged at the rear edges of the main planes, and balancing planes hinged at the outer ends of the main planes.

39. An aeroplane having main weight-supporting planes extending at the respective sides thereof, a third weight-supporting plane arranged over the main planes and forming in connection therewith a dihedral angle, auxiliary planes hinged at the rear edges of the main planes, and balancing planes hinged at the outer ends of the main planes, each of said planes being curved from end to end and curved from front to rear.

40. An aeroplane having a plurality of weight-supporting main planes, and planes for steering the aeroplane in a vertical direction, said main planes being positioned intermediate said steering planes and free from overlapping relation thereto, each steering plane being curved from front to rear and from end to end.

41. An aeroplane having a plurality of weight carrying planes, and a steering plane for controlling the flight in a vertical direction, said steering plane being spaced in a fore and aft direction relatively to said weight supporting planes so as to be free from overlapping relation thereto and said steering plane being curved from end to end and from side to side.

42. An aeroplane having two main weight-supporting planes extending at the respective sides thereof, a third weight-sup-

porting plane extending over the inner portions of the main planes and connected thereto intermediate their ends, balancing planes mounted for movement relative to 5 the outer ends of the two main planes, auxiliary planes hinged at the rear edges of the two main planes, said balancing planes and the auxiliary planes being disconnected from the third weight-supporting plane, and 10 steering planes positioned at the front and

the rear respectively of the main planes, each steering plane being mounted to swing forwardly and rearwardly.

In testimony whereof I have signed my name to this specification in the presence of 15 two subscribing witnesses.

HARLOW T. STOKES.
